[57] CLAIM

The ornamental design for a bottle, as shown and described.

DESCRIPTION

FIG. 1 is an exploded, top perspective view of a bottle showing our new design;
FIG. 2 is a side elevational view with the cap in place, the opposite side being the same in appearance;
FIG. 3 is an elevational view looking from the right of FIG. 2, the opposite side being the same in appearance;
FIG. 4 is a top plan view;
FIG. 5 is a bottom plan view;
FIG. 6 is an elevational view showing another embodiment of our new design;
FIG. 7 is an elevational view looking from the right of FIG. 6, the opposite side being the same in appearance. The top and bottom surfaces of the bottle and the top surface of the cap in the modified form have the same appearance as the respective areas seen in FIGS. 4, 5 and 1.
